UNITED STATES PATENT OFFICE.

LAFE V. PENCE, OF FLINT, MICHIGAN, ASSIGNOR TO GENERAL MOTORS CORPORATION, OF DETROIT, MICHIGAN, A CORPORATION OF DELAWARE.

VALVE-OPERATING MECHANISM FOR INTERNAL-COMBUSTION ENGINES.

Application filed March 12, 1920. Serial No. 365,291.

To all whom it may concern:

Be it known that I, LAFE V. PENCE, a citizen of the United States, and a resident of Flint, county of Genesee, and State of Michigan, have invented certain new and useful Improvements in Valve-Operating Mechanism for Internal-Combustion Engines, of which the following is a full, clear, concise, and exact description such as will enable others skilled in the art to which the invention relates to make and use the same, reference being made therein to the accompanying drawings, which form a part of this specification.

My invention relates to valve operating mechanism for internal combustion engines; and the principal object thereof is to provide valve operating mechanism the operation and adjustment of which will not be disadvantageously affected by the expansion of the cylinder and other parts which occurs when the engine becomes heated, and in which the contraction due to the cooling of the engine can in no event result in a condition of the valve operating mechanism such that the valves will be held off their seats when the engine is cool.

A further object of my invention is to provide improved valve operating mechanism for internal combustion engines in which the parts thereof and the number of the joints or connections through which motion is communicated to the valves are reduced to a minimum, thereby providing valve operating mechanism which will be simple in construction and little affected by wear; which will be quiet in operation, and which will not be likely to get out of adjustment when the engine is in use due to wear of the joints or connections between the elements thereof, or to other causes.

A further object of my invention is to provide improved valve operating mechanism for internal combustion engines in which the force necessary to accomplish the opening of the valves is materially reduced, because of the construction of the parts thereof and their arrangement relative to one another; thus on the one hand providing valve operating mechanism in which the force communicated therethrough to operate the valves is materially reduced, and on the other hand providing valve mechanism in which stiffer springs are or may be used for

accomplishing the closing of the valves than has heretofore commonly been the case. 55

With the above and other objects of invention in view my invention consists in the improved valve operating mechanism illustrated in the accompanying drawings and hereinafter described and claimed; and in 60 such variations and modifications thereof, within the scope of the concluding claims, as will be obvious to those skilled in the art to which my invention relates.

Referring now to the drawings wherein the preferred embodiment of my invention is illustrated:

Figure 1 is a view for the most part in section showing my improved valve operating mechanism as applied to a multiple cylinder internal combustion engine of the V-type or class, wherein the cylinders are arranged at an angle to one another. 65 70

Figure 2 is a fragmentary view upon a larger scale illustrating mechanism whereby 75 and through which a single valve of the engine is operated, the mechanism being associated with a cylinder upon the right hand side of the engine, referring to Figure 1.

Figure 3 is a fragmentary view upon a 80 still larger scale illustrating the mechanism associated with the lower end of one of the pull rods of the valve operating mechanism and the cam whereby the same is operated.

Figure 4 is a fragmentary view showing 85 the upper ends of two pull rods, together with the cross heads and guide mechanism associated therewith, through which motion is communicated to two of the valves of the engine. 80

Figure 5 is a fragmentary view illustrating the connection between the upper end of a pull rod and the stem of a valve which is operated thereby.

Figure 6 is a view showing a section taken 90 upon a transverse plane indicated by the line 6—6, Figure 5.

Referring to the drawings, the reference numeral 6 designates the upper half and 7 the lower half of a two part crank case 100 which is divided along a central horizontal plane passing through the crank shaft 8 of the engine; and 9 designates two cylinder blocks supported by the upper half of the crank case and upon seats or surfaces which 105 are inclined relative to one another, so that

the two cylinder blocks as well as the cylinders 10 within the same are arranged at an angle to one another as in the ordinary form or type of multiple cylinder engine. Each 5 of the cylinder blocks ordinarily has a plurality of cylinders formed integrally with one another and the axes of which when prolonged pass through the axis of the crank shaft 8 of the engine; altho it will be appreciated 10 that my invention is applicable to engines of any type or form and is not limited to engines of the V-type or form, nor to multiple cylinder engines.

The pistons 11, one only of which is shown, 15 are connected with the crank pins of the crank shaft 8, one of which is indicated by the reference numeral 12, through suitable connecting rods 13, 14 as is usual in multiple cylinder engines, and the upper portion of 20 the crank case section 6 is provided with a recess or chamber 15 within which a valve operating cam shaft 16 is rotatably supported in suitable bearings not shown, and which valve operating shaft is driven at the 25 usual two to one ratio from the crank shaft 8 by any suitable driving mechanism which, however, is not shown in the drawings, as the same forms no part of the invention to which this present application relates.

30 The open upper end of the chamber 15 is closed by means of a cover 18, and said chamber is intended to contain a considerable quantity of oil wherein the valve operating shaft as well also as the valve operating levers operated therefrom and herein-after referred to are submerged to a greater or less degree, in order to thereby provide adequate lubrication for the parts in question of the valve operating mechanism. The 35 lubricating system of the engine, however, is not involved in this present application, for which reason the same is not disclosed in detail.

The open upper ends of the cylinders 10 40 within the cylinder blocks are closed by means of cylinder heads 19 secured to said cylinders, and the stems 20 of the supply and exhaust valves of the engine are slidable in bearings 21 secured within passages provided 45 in said heads; one of said valves, its stem, and the sleeve whereby the said stem is guided being shown in Figure 1 and indicated therein by the reference numeral 22, and which valve controls the flow through a passage provided in the head. As a matter of course the valve illustrated in Figure 1 may 50 be either the supply valve or the exhaust valve of the cylinder 10 with which it is associated, as both the supply and exhaust valves 55 are alike so far as concerns the general type thereof and the operating means through which they are opened. Each valve is acted upon by a spring, one of which is indicated by the reference numeral 23, which spring 60 acts between a fixed abutment provided upon

the head and a cup shaped stop or washer 24 secured to the upper end of the valve stem.

The reference numeral 25 designates a cross head through which motion is communicated to the valve stem 20, one such cross head being associated with each of the valves to be operated and all being substantially alike, for which reason the following description will be in the singular; although it will be appreciated that the mechanism 75 described will be duplicated for each valve to be operated by my improved valve operating mechanism. The cross head for one of the valves is shown enlarged and in detail in Figures 5 and 6 of the drawings from 80 which it will be seen that the same is provided with an opening 26 through which the upper end of the valve stem passes, and with a threaded passage above and in line with said valve stem through which an 85 adjusting screw 27 extends and the position of which screw when properly adjusted may be fixed by a lock nut 28 which engages with the upper surface of the cross head; the purpose of the screw and lock nut being to 90 adjust the effective length of the pull rod through which the valve is operated as it will be appreciated that movement is communicated to the valve stem through the screw 27, and that the cross-head as a whole 95 is capable of adjustment upon and relative to the stem of the valve by the said screw.

The cross-head in question is provided with a slot 29 for the reception of the upper properly shaped end 30 of the pull rod 31 100 through which the cross head is operated, the said upper end being secured to the cross head by pins 32' extending through the same. The pull rods are of small diameter, and may in fact be referred to as wires as 105 the valves are operated by tension forces transmitted along and through the said pull rods or wires; from which it follows that inasmuch as said members do not have to withstand compression forces no provision 110 has to be made to prevent the buckling of the said rods and rods or wires of small size, and having little inherent stiffness, may be employed for communicating opening movement to the several valves. 115

The lower ends of the pull rods 31 are secured to yoke members or links 32 as by extending said lower ends into sockets 33 provided at the upper ends of said yokes; and in this connection it will be observed 120 that the upper and lower ends of the pull rods are so formed as to facilitate their connection one with the said socket 33, and the other with the cross head 25 through the slot and pin connection provided at said upper 125 end, as above pointed out. The yoke may be properly referred to as a floating yoke; and the same partakes of both a downward and a sideways motion when an abutment 34 upon its lower end is acted upon by the cam 130

35 upon the cam shaft 16 which operates any particular yoke and valve operated through the same; such movement being due to the fact that the lower end of the yoke is pivotally connected at 36 with the free end of a rocking arm 37, which arm partakes of an oscillatory movement about a shaft 38 as a center and which shaft in turn is supported in bearings 39, see Figure 1, within the 10 lubricant containing chamber 15 above referred to.

It will be seen, referring to Figure 1, that when my invention is applied to a multiple cylinder engine of the V type or form the 15 shaft 38 which supports the oscillating arm 37 associated with a particular valve is upon the side of the valve operating shaft 16 opposite to that of the engine cylinder the valve of which is to be operated by a pull rod 31 the 20 lower end of which is connected with the yoke 32 which is pivotally connected with the particular arm 37 herein contemplated; such a disposition of the parts being present in the 25 operating mechanism for each separate valve. This arrangement, as will be understood from Figure 2 of the drawings, results in valve operating mechanism in which each pull rod 31 moves both downward and toward the engine cylinder a valve of which is 30 operated by the rod in question in each particular case; this statement being true as to the individual valve operating mechanisms associated with each of the various valves.

The pull wires extend through the interiors of housings 40 formed integrally with the cylinder blocks, and through passages 41 formed in the heads 19 of the cylinders. The heads themselves are open at their upper ends so as to permit access to the adjusting screws 27 and to the guiding mechanism for the cross heads hereinafter described; and hoods 42 are secured in place over these openings when the engine is in use which hoods, in connection with the 45 heads and the housings 40, and the lubricant containing chamber 15 and its cover 18, obviously provide a closed protecting casing within which the entire valve operating mechanism is enclosed and protected 50 from injury.

In order to prevent binding of the valve stems 20 as force is communicated to them through the pull rods or wires 31, which obviously act at an angle relative to the line of movement of the valve stem and valve in each particular case, guide rollers 43 are provided adjacent the cross heads 25 and against which rollers flat surfaces 46 upon the cross heads bear, as best shown in Figures 1 and 4 of the drawings. These guide rollers are rotatable upon suitable shafts 47 extending at right angles to the valve stems and which shafts are in turn supported by brackets 48 secured to the upper surface of 65 the heads 19 by means of bolts 49; each

bracket in the embodiment of my invention illustrated serving to support a shaft upon which guide rollers for the cross heads which operate two valves are supported.

These brackets 48 are provided with internal annular channels 50 within which wicks 51 are located which wicks extend downward through a passage 52 provided in the bracket in each instance, and into a oil reservoir 53 formed in the upper surface of 70 the head 19; which construction and arrangement provides for the lubrication of the bearings between the rollers 43 of the shaft 47, as well as for the wearing surfaces between the rollers and the cross head which latter surfaces, however, require little lubrication as the contact between them is a rolling contact in each case. In order to secure and maintain a proper relationship between the brackets 48 and the rollers 43 75 which they carry and the cross heads 25 upon the upper ends of the valve stems one or more dowel pins 54 are provided, which pins extend through openings in the bases of the brackets and serve to definitely position the said brackets.

It will be appreciated that as the valve operating shaft 16 rotates the cam 35 thereupon, referring to Figure 2, will act upon the abutment or cam face 34 of the yoke 32 80 and move said yoke downward, said yoke also partaking of a movement to the right because of the pivotal connection at 36 between its lower end and the oscillating arm 37. This movement of the yoke 32 will move 100 the pull rod or wire 31 downward and to the right; and the upper end of said pull rod will also partake of a movement downward and to the right because of the angular arrangement of the valve stem 20 relative to the said pull rod and which valve stem is obviously capable of movement in an inclined direction only, because of the inclined arrangement of the bearing 21 wherein it is supported. During this downward movement of the valve stem binding between the said stem and the sleeve 21 will be prevented by the rollers 43 which serve as guides for the cross head 25 the flat surface 46 of which moves in engagement with 110 said rollers.

It will be appreciated that valve operating mechanism such as has been above described in detail will be provided for each of the valves of the engine which are to be 120 positively operated; and it may be here stated that when my invention is applied to a multiple cylinder engine of the V-type in the manner illustrated in Figure 1 the abutments 34 of the yokes 32 associated with like 125 valves of oppositely disposed cylinders will be offset, as shown in Figure 4, so that for example one exhaust cam 35 will engage the abutments 34 of two yokes and communicate motion to both of them and to the ex- 130

haust valve of two oppositely located cylinders; while one inlet cam 55 will likewise, and through similarly arranged yokes, communicate motion to the inlet valves of two cylinders also located one upon each side of the engine.

It will be seen that there are open passages leading downwardly from the interiors of the caps 42 through the passages 41, 10 then through the interiors of the housings 40 and to the interior of the lubricant containing chamber 15; so that the lubricant supplied to the chambers 53 and to the guide rollers associated with the cross heads is free 15 to return to the lubricant containing chamber 15. Suitable pumping mechanism may be provided for forcing lubricant from the chamber 15 to the interior of the chambers 53; from which it returns to the said chamber 15 in a continuous cycle, thus maintaining 20 an adequate lubrication of the valve mechanism in its entirety; altho as hereinbefore explained the lubricating system of the engine is not involved in this present 25 application, and is consequently not illustrated in detail.

The adjustment of the screws 27 will be such that when the engine is running and is in a heated condition the valve lash or lost motion between the cams upon the valve operating shaft and the abutments upon the yokes through which the pull rods are operated will be at a minimum; which lost motion need be only so much as to insure 35 that the valves will not be held off their seats slightly, because of insufficient or no lost motion at all in the valve operating mechanism, when the engine is in a heated condition. When the engine is cold, however, the reduction in length of the cylinders and heads due to contraction of said 40 members will increase the valve lash which, however, will in no way interfere with the operation of the engine, as the reduced opening movement of the valves will in no way interfere with their closing tightly upon 45 their seats and the proper operation of the engine at starting.

One of the advantages of my invention 50 over prior constructions will be appreciated from the above explanation of operation for, in valve operating mechanisms in which the opening movement of the valves is communicated to them through push rods operating 55 under compression stresses, the contraction of the engine cylinder upon cooling will (if the adjustment is such as to reduce the lost motion to a minimum when the engine is cold, as is necessary to secure as 60 great a valve opening as possible when the engine is hot) take up the lost motion and often result in lifting the valves slightly off their seats, thus making the starting of the engine difficult because of the failure of the 65 valves to seat tightly; while the expansion

of the engine as it becomes heated will in mechanisms of the old type here referred to reduce the opening movement communicated to the valves when as a matter of fact the valves should open to their maximum extent 70 when the engine is heated and in operation. In my improved valve operating mechanism, on the contrary, no degree of contraction can result in the holding of the valves off their seats; while the elongation of the cylinders 75 as the engine becomes heated will take up such excess lost motion as may be present when the engine is cold and secure a degree of opening of the valves corresponding with that required for the most efficient operation 80 of the engine, and which lost motion is determined by the adjustment of the mechanism when the engine is hot and under the precise temperature conditions under which maximum efficiency should be provided for. 85

It will be further appreciated that the valve lifters and rocker arms ordinarily present in prior valve operating mechanisms wherein the valves are operated through push rods are eliminated in my improved 90 valve operating mechanism, thus greatly simplifying the said mechanism and reducing the number of parts thereof; with an accompanying elimination of wear at several joints or points of contact, and of the greater 95 part of the noise heretofore often present in valve operating mechanisms and due to looseness of joints, and in general to lost motion throughout the mechanism in question.

In fact, in my improved valve operating 100 mechanism the yoke, the pull rods or wire, the cross head, and the valve in its entirety are in effect and as to each valve a single unitary device or structure; thus materially simplifying the valve operating mechanism, 105 reducing its initial cost, and providing a mechanism which is less likely to get out of adjustment or to require attention when the engine is in use than has heretofore commonly been the case. 110

Finally, the angular arrangement of the valves to be operated relative to the pull rods or wires through which motion is communicated thereto provides valve operating 115 mechanism in which the force necessary to open the valves is reduced, or, assuming a given opening force available, then provides mechanism in which a stiffer spring may be used to close the valve, both of which are features of advantage in valve operating 120 mechanism; and provides also valve operating mechanism in which such wear as occurs has less effect in producing lost motion in the mechanism that would be the case if the lines of opening movement of the valves 125 were not inclined relative to the pull rod whereby the valves are opened.

Having thus described and explained my invention, I claim and desire to secure by Letters Patent: 130

1. In an internal combustion engine, a cylinder head having a passage; a reciprocating valve carried by said head and adapted to control the flow through said passage, and which valve is provided with a stem extending therefrom; a cross head carried by said stem and having a bearing surface; a bracket carried by said head; a shaft carried by said bracket and which shaft extends at right angles to said valve stem; a roller supported by said shaft and the periphery of which is in engagement with the bearing surface aforesaid of said cross head; a pull rod the upper end of which is connected with said cross head, and which pull rod acts at an angle to the path of movement of said valve stem in transmitting movement thereto; a rotating valve operating shaft; a yoke with which the lower end of said pull rod is connected, and which yoke is provided with an abutment located beneath said valve operating shaft; an oscillating arm the free end of which is pivotally connected with said yoke, and which arm is supported at a point located at the opposite side of said valve operating shaft from that upon which said yoke and pull rod are located; and a cam carried by said valve operating shaft and adapted to engage said abutment to thereby move said yoke downward. 70 75
- 10 15 20 25 30
4. In an internal combustion engine, a cylinder head having a passage; a reciprocating valve carried by said head and adapted to control the flow through said passage, and which valve is provided with a stem extending therefrom; a cross head carried by said stem and having a bearing surface; a bracket carried by said head; a shaft carried by said bracket and which shaft extends at right angles to said valve stem; a roller supported by said shaft and the periphery of which is in engagement with the bearing surface aforesaid of said cross head; a pull rod subjected to tension and the upper end of which is connected with said cross head, and which pull rod acts at an angle to the path of movement of said valve stem in transmitting movement thereto; a yoke with which the lower end of said pull rod is connected; an oscillating arm the free end of which is pivotally connected with said yoke; a rotating valve operating shaft; and a cam carried by said valve operating shaft and adapted to engage an abutment upon said yoke to thereby transmit motion thereto and to said pull rod. 90 95 100 105
- 35 40 45 50 55 60 65
5. In an internal combustion engine, a cylinder head having a passage provided therein; a reciprocating valve carried by said head and adapted to control the flow through said passage, and which valve is provided with a stem extending therefrom; a cross head carried by said stem and having a bearing surface; a roller against the periphery of which said cross head bears, and which serves as a guide therefor; a pull rod the upper end of which is connected with said cross head, and which pull rod acts at an angle to the path of movement of said valve stem in transmitting movement thereto; a reciprocating yoke with which the lower end of said pull rod is connected; an oscillating arm the free end of which is pivotally connected with said yoke; a rotating valve operating shaft; and a cam carried by said valve operating shaft and adapted to engage an abutment upon said yoke to thereby transmit motion thereto and subject said pull rod to tension. 110 115 120 125
6. In an internal combustion engine, a cylinder head having a passage formed there- 130
- 135
2. In an internal combustion engine, a cylinder head having a passage; a reciprocating valve carried by said head and adapted to control the flow through said passage, and which valve is provided with a stem extending therefrom; a cross head carried by said stem and having a bearing surface; a bracket carried by said head; a shaft carried by said bracket and which shaft extends at right angles to said valve stem; a roller supported by said shaft and the periphery of which is in engagement with the bearing surface aforesaid of said cross head; a pull rod subjected to tension and the upper end of which is connected with said cross head, and which pull rod acts at an angle to the path of movement of said valve stem in transmitting movement thereto; a yoke with which the lower end of said pull rod is connected; an oscillating arm the free end of which is pivotally connected with said yoke; a rotating valve operating shaft; and a cam carried by said valve operating shaft and adapted to engage an abutment upon said yoke to thereby transmit motion thereto and to said pull rod. 100
3. In an internal combustion engine, a cylinder head having a passage formed therein; a reciprocating valve carried by said head and adapted to control the flow through said passage, and which valve is provided with a stem extending therefrom; a cross head carried by said stem and having a bearing surface; a roller against the periphery of which said cross head bears, and which serves as a guide therefor; a pull rod the upper end of which is connected with said cross head, and which pull rod acts at an angle to the path of movement of said valve stem in transmitting movement thereto; a reciprocating yoke with which the lower end of said pull rod is connected; an oscillating arm the free end of which is pivotally connected with said yoke; a rotating valve operating shaft; and a cam carried by said valve operating shaft and adapted to engage an abutment upon said yoke to thereby transmit motion thereto and subject said pull rod to tension. 120
4. In an internal combustion engine, a cylinder head having a passage formed there- 130

in; a reciprocating valve carried by said head and adapted to control a flow through said passage, and which valve is provided with a stem extending therefrom; a cross head carried by said stem; a pull rod the upper end of which is connected with said cross head; a rotating valve operating shaft; a yoke with which the lower end of said pull rod is connected, and which yoke is provided with an abutment located beneath said valve operating shaft; an oscillating arm the free end of which is pivotally connected with said yoke; and a cam carried by said valve operating shaft and adapted to engage said abutment to thereby depress said abutment and subject said pull rod to tension.

7. In an internal combustion engine, a cylinder head having a passage formed therein; a reciprocating valve carried by said head and adapted to control the flow through said passage, and which valve is provided with a stem extending therefrom; a pull rod subjected to tension and the upper end of which is operatively connected with said valve stem, and which rod acts at an angle to the path or movement of said stem in transmitting movement thereto; a rotating valve operating shaft; a yoke with which the lower end of said pull rod is connected, and which yoke is provided with an abutment located beneath said valve operating shaft; an oscillating arm the free end of which is pivotally connected with said yoke; and a cam carried by said valve operating shaft and adapted to engage said abutment.

8. In an internal combustion engine, a cylinder having a passage adjacent its upper end; a reciprocating valve adapted to control the flow through said passage, and which valve is provided with a stem extending therefrom; a pull rod operatively connected with said valve stem through which movement is communicated thereto by tension transmitted through said pull rod; a rotating valve operating shaft; a cam carried by said shaft; and means through which said cam acts to move said pull rod both longitudinally and in a direction transverse to its axis to thereby communicate motion to said valve through said pull rod by tensile force transmitted along said rod.

9. In a multiple cylinder internal combustion engine, two cylinders arranged in V relation to one another; a rotating valve operating shaft located between said cylinders and adjacent their lower ends; an oscillating arm supported adjacent one of said cylinders and extending toward the other cylinder; a reciprocating yoke one end of which is pivotally connected with the free end of said oscillating arm and which yoke is provided with an abutment which lies beneath said valve operating shaft, and the other end of which yoke is connected

with the lower end of a pull rod located adjacent and extending upwardly alongside the other of said cylinders; a valve located at the upper end of said last mentioned cylinder and adapted to control a passage leading thereinto; means whereby and through which the upper end of said pull rod is operatively connected with said valve to open the same by tensile force transmitted through said pull rod; and a cam upon said valve operating shaft and adapted to engage the abutment aforesaid to thereby move said yoke downward.

10. In a multiple cylinder internal combustion engine, two cylinders arranged in V relation to one another; a rotating valve operating shaft located between said cylinders and adjacent their lower ends; an oscillating arm supported adjacent one of said cylinders and extending toward the other cylinder; a pull rod located adjacent and extending upwardly and alongside the other of said cylinders, and the lower end of which pull rod is connected with said oscillating arm; a cam carried by said valve operating shaft; an abutment engaged by said cam and operatively connected with said pull rod to thereby subject said pull rod to tension; a valve located at the upper end of said second mentioned cylinder and adapted to control a passage leading thereto; and means whereby and through which the upper end of said pull rod is operatively connected with said valve.

11. In a multiple cylinder internal combustion engine, two cylinders arranged in V relation to one another; a rotating valve operating shaft located between said cylinders and adjacent their lower ends; two oscillating arms supported one adjacent each of said cylinders and which arms extend each toward the other cylinder; two reciprocating yokes the lower ends of which are pivotally connected one with each of said oscillating arms and which yokes are provided each with an abutment, which abutments lie beneath said valve operating shaft, and the other ends of which yokes are connected with the lower ends of two pull rods located one adjacent and extending upward alongside each cylinder; valves located at the upper ends of said cylinders and adapted to control passages leading one into each of said cylinders; means whereby and through which the upper ends of said pull rods are operatively connected one with each of said valves; and a cam upon said valve operating shaft so located and arranged as to engage both the abutments aforesaid, to thereby operate both said valves from a single cam.

In testimony whereof I affix my signature.

LAFE V. PENCE.
